UNITED STATES PATENT OFFICE.

HENRY R. VAN EPS, OF PEORIA, ILLINOIS.

DESIGN FOR A FENCE-PANEL.

SPECIFICATION forming part of Design No. 23,146, dated March 20, 1894.

Application filed January 15, 1894. Serial No. 496,989. Term of patent 7 years.

To all whom it may concern:

Be it known that I, HENRY R. VAN EPS, a citizen of the United States, residing at Peoria, in the county of Peoria and State of Illinois, have invented a certain new and useful Design in Fencing; and I do hereby declare that the following is a full, clear, and exact description of the invention, which will enable others skilled in the art to which it appertains to make and use the same.

My invention relates to a new and original design for a fence panel.

Reference is had to the accompanying drawing showing the particular design.

The figure shows a section of my fence panel design in elevation, this view being deemed sufficient to duly illustrate my design.

The leading feature of my design consists

in the parallel rails, the alternately disposed short and long pickets, the scroll shaped parts intervening between the middle and top rails and connected with each alternate long picket, the scroll shaped parts connected with and carried upon the top face of the top rail, and connected with the upper extremities of the long pickets, and the ornamental cap carried upon each of the respective long pickets.

What I claim is—

The design for fence panel as herein shown and described.

In testimony whereof I affix my signature in presence of two witnesses.

HENRY R. VAN EPS.

Witnesses:

WILLIAM SCOTT,
B. R. MILES.
